UNITED STATES PATENT OFFICE

CHARLES A. BROWN, OF GARDNER, MASSACHUSETTS, ASSIGNOR TO HEYWOOD-WAKEFIELD COMPANY, OF BOSTON, MASSACHUSETTS, A CORPORATION OF MASSACHUSETTS

PEDESTAL FOR FURNITURE OR THE LIKE

Application filed January 5, 1927. Serial No. 159,200.

This invention relates to pedestals for furniture or the like and has for its object to provide such a pedestal which may support an object rigidly at any desired height within its range and which presents a relatively smooth surface readily kept clean.

To attain these objects the pedestal comprises a pair of lapping telescopically related sections, the inner section having a central stem with which clamping means are associated to hold the sections in any desired adjustment with respect to the extent of telescoping. By forming the stem tapered an accurate and secure fixing of the sections in adjusted positions and against relative axial turning is insured and the side engagement between the telescoping portions provides guiding engagement therebetween spaced in annular arrangement about a longitudinal axis of the sections, thus securing rigidity, preventing misalignment of the sections with consequently undesirable tilting of the object supported, and also presenting a relatively smooth exterior surface of pleasing appearance and which is easily kept clean.

For a more complete understanding of this invention reference may be had to the accompanying drawings in which

Figure 1 is a vertical central cross section through a pedestal shown as applied to a school desk.

Figure 2 is a perspective of the upper section.

Figure 3 is a perspective of the lower section.

Figure 4 is a perspective of a portion of the securing means.

As shown in these figures, the pedestal comprises lower and upper telescopically related members 1 and 2. The member 1, as shown in Figures 1 and 3, comprises an outwardly flaring base portion terminating in a flange 3 which may be provided with openings for the passage of bolts or screws to attach the pedestal to the floor. Above the flaring portion the section 1 is shown as formed tubular in cross section, tapering slightly at its upper end as at 4 as shown in Figure 1. This member may be formed of sheet metal which may be constructed in accordance with

the method disclosed in my application for patent, Serial No. 758,384, filed December 27, 1924.

The top face of the tubular portion 5 is reinforced by means of a circular block 6 riveted thereto, this reinforcing block serving to support an upwardly extending stem 7 to smaller cross sectional area than that of the tubular portion 5. One of the side portions 8 of this stem is formed angularly, the outer edge of the angle extending parallel to the axis of the section. Opposite to this angle a flat face 9 on the spindle is formed tapered upwardly.

The upper section 2 comprises a head 10 formed in a suitable shape to be fixed to the article to be supported, for example, as shown in Figure 1 to the desk 11. Below this head 10, the upper section is formed tubular, as at 111, of such an internal diameter that it may slide over the portion 5 of the section 1 in close telescopic relation thereto to engage about substantially its entire periphery so as to prevent entry of foreign matter therebetween. Fixed within the tubular portion 111 is a clamping block 12 shown in Figure 4 as made from a substantially U shaped sheet metal piece having a notch 13 cut therein to provide spaced upper and lower relatively narrow edge faces 15 with which the angular face 8 of the spindle may engage. This U shaped piece is shown as provided with lugs 16 which may be passed through suitable perforations in the wall of the tubular member 111 and be riveted externally thereof, thus to fix the member 12 in position.

Diametrically opposite to this member the tubular portion 111 is perforated for the reception of an internally threaded block 20 which may be made fast to the portion 111 as by means of rivets 21. Through this threaded block 20 may extend an adjusting screw 22 having a head accessible outside of the portion 111, the inner end of this screw engaging on the tapered face 9 of the spindle pressing the spindle against the member 12 and acting to hold the pedestal parts 1 and 2 in any adjusted position. The annular face 8 engaging against the edges 15 spaced apart one above and the other below

the axis of the bolt 22, and the bearing of this bolt on the tapering face 9 act to hold the sections 1 and 2 against relative axial movement even during adjustment. The 5 lower portion of the tubular element 111 engages about the outer face of the portion 5 of the lower section 1 at points arranged circumferentially about the vertical axis of the sections. This effectually prevents the 10 upper section from tilting in any direction to throw it out of vertical alinement with the lower section 1 and the close engagement between the two sections presents a relatively smooth surface which it is easy to keep 15 clean.

15 While the parts as shown are made of sheet metal and may be formed up readily in accordance with the method disclosed in my application for patent hereinbefore referred to, it should be evident, of course, 20 that they might otherwise be formed, if desired, and that various other changes and modifications might be made without departing from the spirit or scope of this invention as defined by the appended claims.

25 I claim:

1. A device of the class described comprising a pair of telescopically related tubular sheet material sections, a stem of smaller 30 cross sectional area than the inner section projecting from its inner end lengthwise thereof, a block within the outer section against which said stem bears, and a screw accessible from without said outer section 35 and actuatable to clamp said stem against said block to fix said sections in adjusted position.

2. A device of the class described comprising a pair of telescopically related tubular sections, a stem of smaller cross sectional area than the inner section projecting from 40 its inner end and lengthwise thereof, a block within the outer section and having spaced edge portions against which said stem bears, 45 and means accessible from without said outer section and engaging said stem opposite to said block and between said edges for clamp- ing said stem against said block.

50 In testimony whereof I have affixed my signature.

CHARLES A. BROWN.
